UNITED STATES PATENT OFFICE.

HARRIETTE GROSS COZZINO, OF NEW YORK, N. Y.

DESIGN FOR A HAT-SUPPORT.

SPECIFICATION forming part of Design No. 27,136, dated June 1, 1897.

Application filed April 13, 1897. Serial No. 632,027. Term of patent 7 years.

To all whom it may concern:

Be it known that I, HARRIETTE GROSS COZZINO, a citizen of the United States, residing at New York city, in the county and State of New York, have invented and produced a new and original Design for a Hat-Support for Theater-Chairs, of which the following is a specification, reference being had to the accompanying drawings, forming a part thereof, 5 in which—

Figure 1 is a perspective view of a hat-support embodying the features of my design, and Fig. 2 is a side elevation of said support.

The design is particularly adapted to a hat-support for theater-chairs; and it has for its object to provide an article of the above-named character which will be both useful and ornamental and which will also enable a person to arrange the toilet when desired.

20 The leading feature of the design consists in a body A, which is curved in a manner corresponding to the curvature of the back of a

theater-chair, a front member B, whose outer face D is capable of producing a reflection, and an intermediate member C, connecting 25 the front and the back members, the intermediate member having a downward and outward inclination, bringing the lower edge of the reflecting member to a decidedly-lower plane than the lower edge of the body member. 30

Another feature of the design consists in imparting to the back member A a bifurcated shape, as at E, and imparting to the front member a cylindrical contour at its upper edge, the lower side edges being more or less 35 straight, and, further, in giving the front member B a rearward inclination.

I claim—

The design for a hat-support for theater-chairs, herein shown and described.

HARRIETTE GROSS COZZINO.
